UNITED STATES PATENT OFFICE.

ALFRED P. KUTSCHE AND ARTHUR A. WINTER, OF MILWAUKEE, WISCONSIN.

WINDOW-SASH LOCK.

Application filed December 20, 1921. Serial No. 522,656.

To all whom it may concern:

Be it known that we, ALFRED P. KUTSCHE and ARTHUR A. WINTER, both citizens of the United States, and residents of Milwaukee, 5 in the county of Milwaukee and State of Wisconsin, have invented certain new and useful Improvements in Window-Sash Locks; and we do hereby declare that the following is a full, clear, and exact description thereof.

Our invention relates to a new and improved window sash lock for locking a window in closed position and which may also be used for supporting the upper sash in 15 any intermediate position to which it may be adjusted.

The primary object of the invention is to provide a simple and inexpensive device of this character which may be easily assembled and installed.

More specifically the invention comprises a bolt and housing, each made from a single casting, the device being assembled by simply laying the bolt in suitable guideways 25 provided in the housing. The bolt being held and accurately guided between the housing and the upper rail of the lower sash to which the device is secured.

The invention will be more fully understood upon reference to the accompanying drawing, in which—

Figure 1 represents a vertical sectional view thru the invention as it appears when attached to a window, and

Figure 2 is a bottom plan view of the housing with the bolt laid therein.

Referring more particularly to the drawing, the numeral 5 indicates a ratchet bar which is secured to the lower portion of the stile 6 of the upper sash. A housing 7 is formed with lateral flanges 8 which are secured by screws, or the like, to the upper rail 9 of the lower sash, and is provided with opposed slots 10 and 11 in its end walls 40 which slidably receive a bolt 12, the projecting end 13 of which is adapted to engage any one of the teeth of the ratchet bar 5. The bolt is provided with a head 14 for manipulating the same, and also has a cross head 15 formed thereon, and having shoulders 16 which are normally held in engagement with the adjacent end wall of the housing by means of a coil spring 17 which surrounds the shank of the bolt.

The housing 7 and the bolt 12 are each 55 cast in a single piece. In assembling, the coil spring 17 is first placed about the shank of the bolt and the latter is laid in the slots 10 and 11 and the housing attached to the rail 9 in such a position that the projecting 60 end of the bolt will engage one of the teeth on the ratchet bar to hold the upper sash in the position to which it has been adjusted. The bolt also has formed, thereon, a lug 18 which is guided over the upper surface of 65 the rail 9 and in connection with the cross head 15, which is guided within the housing, provides an accurate guide for the bolt when it is manipulated by means of the head 14.

From the above description, it will be seen 70 that we have provided an extremely simple construction which may be manufactured at a minimum cost and quickly installed.

While we have shown and described specifically one form in which our invention 75 may be embodied, it will be understood that minor modifications in form and proportion may be made without departing from the scope of the invention as claimed.

We claim:

In a device of the class described, a one piece rectangular hollow housing having an open bottom and slotted end walls, a one piece bolt slidably held within said housing and having an enlarged tongue projecting 85 through the slot in one of said end walls and having an enlarged shouldered portion adapted to contact with the inner side of said end wall to limit the outward movement of said bolt, said bolt having a straight reduced portion extending through the slot in the other end wall and terminating in an operating head in axial alignment with such reduced portion, and a coiled spring surrounding said reduced portion and bearing 90 at one end against said last mentioned wall and at its other end against said shouldered portion, said bolt having a downwardly extending lug adjacent said operating head adapted to cooperate with said shouldered portion to guide said bolt when said housing is attached to a flat surface.

In testimony that we claim the foregoing we have hereunto set our hands at Milwaukee, in the county of Milwaukee and 105 State of Wisconsin.

ALFRED P. KUTSCHE.
ARTHUR A. WINTER.
